ABSTRACT OF THE DISCLOSURE

Apparatus for facilitating inventory control of record albums by attaching an "IBM" card in a manner resisting accidental removal but enabling clean intentional removal. The apparatus comprises a pair of tape strips, one with light tack adhesive that fastens one end of the card to the album cover, and the other of high tack adhesive that permanently fastens an opposite corner of the card to the album cover. The IBM card has a perforation along the permanently fastened corner to enable the card to be neatly torn away.

BACKGROUND OF THE INVENTION

(1) Field of the invention

This invention relates to apparatus for use in inventory control.

(2) Description of the prior art

Phonograph records are often packaged as albums containing a single record in a cardboard jacket. The jacket is protected against dust and against opening by browsing customers, by means of a transparent plastic cover which is meant to be discarded. The albums are commonly merchandised in self-service stores where they are kept in rows, one behind the other, and where customers may lift out and replace albums until one is found which is to be purchased.

Tight inventory control is very important in popular record merchandising because particular record titles may have sudden but brief rises in sales, and unless they are quickly restocked many sales may be lost. A good method for keeping track of record albums sold is to attach labels to them, which are to be removed by the salesclerk at each purchase. The labels carry the stock number of the record title in a machine-readable code, and are gathered every week or so for automatic re-ordering of record stocks.

The use of machine-readable labels for inventory control has not been highly successful because salesclerks often do not bother to remove them. If the labels are easily removable to encourage salesclerks to remove them, they may become accidentally removed during customer browsing. One type of small machine-readable tag called a Kimbal tag has been tried, wherein the opposite tag ends are permanently fixed to the album cover. These tags have perforations at opposite ends, and the salesclerk is supposed to place a finger under the tag and lift it up to tear along the perforations. However, even when clerks bother to try removal, they often tear the tags within the area bounded by the perforations and thereby render it difficult or impossible to read.

2

OBJECTS AND SUMMARY OF THE INVENTION

One object of the present invention is to provide means for fastening inventory control labels in a manner that resists accidental removal, yet which enables easier intentional removal without damage.

Another object is to provide a label for a record cover which encourages more accurate inventory control.

In accordance with the present invention, means are

10 provided for more effectively fastening inventory control labels comprising two strips of tape. One strip, which has a light tack adhesive, extends along one edge of the label. The other strip, which has a high tack adhesive, extends across a corner of the label on an edge opposite the first strip. The label has a perforation line along the corner which is held by the high tack strip of tape. Label removal is accomplished by lifting the end which is held by the light tack strip, and tearing along the perforation line. The light tack adhesive prevents damage to the label or 20 the depositing of adhesive thereon, while the corner perforation can be easily torn to encourage label removal and reduce the likelihood of damage.

In accordance with one embodiment of the invention, a label in the form of the well-known "IBM" card is utilized to control inventory of record albums. Such cards are relatively large as compared with small inventory labels heretofore used on items of the size of record albums, and are constructed of a high grade cardboard as opposed to ordinary paper labels. This, plus the fact 30 that a large number of people likely to be employed as store clerks have become accustomed to treating IBM cards carefully, increases the likelihood that these labels will be removed at the time of the sale, and in a careful manner.

35 The IBM-type cards are fastened to the rear of the album cover, with the length of the card extending vertically when the front of the album is in its normal position. The light tack strip extends along the lower edge of the card. This protects the bottom corners of the card from 40 catching when an album is reinserted in a tightly packed row of albums. A small, high-tack tape strip permanently fastens one of the upper corners to the album cover. This strip is positioned just outside the perforation line across the corner of the card. The cards carry a price marking 45 in addition to a machine-readable inventory code. The permanent fastening of the label at one point (an upper corner) prevents a customer from illegally switching the label from a low-priced album to a high-priced album, as well as preventing accidental removal.

50 The novel features of the invention are set forth with particularity in the appended claims. The invention will be best understood from the following description when read in conjunction with the accompanying drawings.

55 BRIEF DESCRIPTION OF THE DRAWINGS

FIG. 1 is a front perspective view of a row of record albums displayed for retail sale, the albums having inventory control apparatus on the backs thereof;

FIG. 2 is a perspective rear view of a record album with an inventory control label fastened thereto by fastening means in accordance with the invention; and

FIG. 3 is a partial rear perspective view of an album, showing the manner of removal of an inventory control label therefrom.

3
**DESCRIPTION OF THE PREFERRED
 EMBODIMENTS**

FIG. 1 shows a typical manner of retail record merchandising wherein albums are arranged in a row 10, one behind the other, in a box-like stand 12. The front face 14 of each album faces forward, and customers browse through the row, occasionally lifting an album partway out of the row for a better look, and sliding it back into the row. An inventory control label or card 16 with indicia in the form of punched holes that identify the album is attached to the rear face 18 of each album. When a customer desires to purchase an album, he takes it to a check-out counter, where a clerk removes the card 16 after the purchase. At periodic intervals such as every week, the cards are collected to determine the quantities of each record title that have been sold, to aid in re-ordering.

As shown in FIG. 2, the album comprises a cardboard jacket or folder 20 which holds a record, the size of the album typically being 12 $\frac{3}{4}$ inches square. A transparent cover 22 completely surrounds the folder to protect the album from dust and to prevent unauthorized removal of the record from the folder. The rear face 18 of the album typically has an area 24 which carries a list of the contents, that is, the titles of songs on the enclosed record. The inventory control card 16 is mounted beside the content-listing area 24 to prevent its obstruction.

The inventory control card 16 is of the IBM card type which is approximately 7 $\frac{3}{8}$ inches by 3 $\frac{1}{4}$ inches, and of cardboard which is approximately 7 thousandths inch thick. It contains punched holes 21 which define the stock number of the particular album title to which it is attached. An upper portion 23 of the card has space for receiving a price marking. The card is mounted with its length extending vertically when the album is in the normally displayed position wherein the front face is "right-side-up." It is preferable to provide a card with a length at least one-half the height of the album, in order that salesclerks treat it as an important item, to be carefully removed and stored.

The card 16 is mounted on the plastic cover 22 by two strips of tape 26 and 28 which lie on the card and areas of the cover immediately adjacent to it. One strip 26 extends along the bottom edge 30 of the card. The other strip 28 extends across a corner 32 which lies on the upper portion 23 of the card, the corner 32 being one of the two corners 32 and 36 which lie opposite the edge 30. The lower strip 26 has a light tack adhesive of the pressure sensitive type on the side facing the card and album cover. Such adhesives adhere more strongly to a smooth surface, such as the plastic cover 22, than to a rough surface such as the cardboard card, and form an easily separated joint with the card. The card 16 has a natural or non-slick surface so that, although it may be relatively smooth to the touch, it is microscopically rough and only a small area contacts the pressure sensitive adhesive. The upper strip 28 has a high tack adhesive so that it forms a substantially permanent union between the cover 22 and corner 32 of the card.

The card 16 has a perforation line 34 formed along the corner 32 immediately within the area crossed by the upper tape strip 28. This line separates the main body portion of the card, which comprises the entire card except for the area at its corner 32, from the secondary portion at the corner 32. The location of the perforation line at this area enables removal of most of the card even though the corner 32 is permanently fastened in place.

When a record purchase is made, the salesclerk removes the card 16 in the manner shown in FIG. 3. The corner 36, which is free of attachment to the cover, is lifted and the fingers of the hand are slipped under the card. The lower portion of the card is lifted to remove the lower edge 30 from the lower strip 26 of tape. The light adhesive character of the tape, particularly with regard to the cardboard card, results in its release from the card merely

by lifting the card. Such removal results in the absence of any adhesive residue on the card which might hamper its machine processing. The weak adhesion also prevents delamination of the card which would occur with high tack adhesive. Thus, the main body portion of the card is cleanly removed. With all but the corner 32 of the card freed, the salesclerk presses a fingernail along the perforation line on the side containing the tape strip 28, and tears the card along this line.

10 The tearing of the card along the perforation line 34 is made by lifting up the rest of the card while holding down the corner 32. If the perforations are not made properly, the card has a tendency to tear outwardly toward the portion held by the tape 32. This prevents damage to the 15 main body portion of the card which contains the article-identifying indicia. If necessary, the removed card can be later cut along the perforation line.

The two strips of tape hold the card securely during typical handling by browsing customers. The lower edge 20 30 is well secured against "catching," when an album is pushed down into the stack after a customer has partially lifted it. The permanent bond provided by the upper strip 28 prevents a customer from removing a card and replacing it with another from a lower priced album, since the 25 corner portion 32 cannot be cleanly removed. Also, it helps to retain the card to the album even in the rare instances when the bottom edge 30 has been accidentally removed from the cover.

The strips 26 and 28 can be easily applied to the album 30 by merely pressing them on the card when the card is placed on the album cover. The pressure sensitive adhesive on the lower strip 26 automatically makes a moderately strong bond with the plastic cover 22 and an easily releasable bond with the cardboard card. The high tack 35 adhesive on the corner strip 28 automatically permanently joins the card and cover. The fact that the two strips of tape remain on the album cover 22 after the sale is made generally is not a detriment. This is because the customer 40 usually removes the cover from the cardboard jacket, or if he does not, the fact that there are tape strips left thereon usually does not matter to him.

Although particular embodiments of the invention have been described and illustrated herein, it is recognized that modification and variations may readily occur to those skilled in the art, and consequently, it is intended that the 45 claims be interpreted to cover such modifications and equivalents.

What is claimed is:

1. Apparatus for inventory control of articles which 50 are offered for sale comprising:

an inventory label of substantially rectangular shape disposed against said article, said label having indicia thereon identifying said article;

55 a first strip of tape with light tack adhesive, extending along a first edge of said label and an area of said article adjacent to said first edge;

a second strip of tape with high tack adhesive extending across a first corner of said label which is opposite said first edge thereof; and

means defining a separation line extending across said 60 first corner immediately within the position of said second strip of tape.

2. Apparatus for inventory control of flat articles which 65 are offered for sale by displaying them in stacks, one behind the other, comprising:

an inventory label disposed against a face of said article, said label having indicia thereon identifying said article;

first means for attaching an upper portion of said label 70 to said article, in a permanent manner;

a strip of tape with easily releasable adhesive for attaching a lower portion of said label to said article in a manner for ready removal, to prevent catching of said label when said article is inserted into said stack; and

means defining a separation line between said first and second portions of said label.

3. The apparatus described in claim 2 wherein: said indicia defining said article is on said lower portion of said label.

4. The apparatus described in claim 2 wherein: said indicia defining said article is on said lower portion of said label and is in a machine-readable code.

5. The apparatus described in claim 2 wherein: said first means for attaching an upper portion of said label to said article comprises a strip of tape with high tack adhesive.
